UNITED STATES PATENT OFFICE.

NATHAN SCHWAB, OF NEW YORK, N. Y.

BOTTLE-STOPPER.

SPECIFICATION forming part of Letters Patent No. 360,055, dated March 29, 1887.

Application filed July 22, 1886. Serial No. 208,754. (Model.)

To all whom it may concern:

Be it known that I, NATHAN SCHWAB, a citizen of the United States, residing at New York, in the county of New York and State 5 of New York, have invented certain new and useful Improvements in Stoppers for Bottles; and I do hereby declare the following to be a full, clear, and exact description of the invention, such as will enable others skilled in the 10 art to which it appertains to make and use the same, reference being had to the accompanying drawings, which form part of this specification.

My invention relates to an improvement in 15 stoppers for bottles, jars, and like vessels, and in the seat adapted to receive them, and has special reference to that class known as "screw-stoppers;" and it consists in making the same as hereinafter described, and more particularly 20 pointed out in the claims.

In the use of glass or other screw-stoppers of vitreous material heretofore used, it has become a recognized fact that great danger arises from the frequently chipping off and 25 falling down into the liquid in the bottle to be consumed as medicine, or to be drank, small sharp portions of the screw-thread, when the stopper is firmly turned into its seat to make the bottle air-tight; and the object of my in- 30 vention is to overcome this serious objection by providing a screw-stopper and seat of such form and material as to obviate the liability of the chipping off of small spicula of the material and its falling into the liquid of the bot- 35 tle, thereby endangering the life and health of the person who consumes it, and to form a more perfect air-tight stopper for the bottle than can be made by the use of unyielding or vitreous material.

40 In the drawings, Figure 1 represents a plan view of my improved stopper; Fig. 2, a part vertical sectional view of the neck or seat into which the stopper is screwed. Fig. 3 shows the stopper inserted in the bottle. Fig. 4 is 45 a detail view showing the neck of the bottle in section before the socket is inserted. Fig. 5 shows the socket removed from the bottle. Fig. 6 is a plan view showing the layers of material in the stopper.

50 Like letters of reference refer to correspond- ing parts in each figure of the drawings.

A represents my improved stopper, made solid from one piece of rolled and compressed leather, having male screw-threads *a* formed on the periphery of its body. The blank from 55 which the stopper is made is cut of suitable size and form, and has one of its surfaces coated with glue or other adhesive substance, and is tightly rolled together, as shown at *d*, on its adhesive side, with portions of its cut 60 end turned in to form the head. It is then compressed in a die to make it regular in shape and to form screw-threads thereon, when it is allowed to dry, and is ready for use.

B represents a bottle, which may be made 65 in any desired shape, having a mouth, *b*, reinforced around its edge. The neck of the bottle is made of a length equal to the length of the screw-threaded portion of the stopper which it is desired to use in it, and has on its 70 inside a recess, *C*, with projections *c* extending therein.

A socket, *D*, made of rolled leather formed around a mandrel, and having a female screw-thread on its inner side, is placed within the 75 recess *C*, and is secured therein by means of glue or other strong adhesive substance, and is kept in place by the projections *c*, which press into its sides, and, together with the adhesive substance, prevent it from turning or 80 working loose when the stopper is inserted or removed.

I am aware that it is not new to form a screw-stopper of elastic material; but many of those now in use are found to be objectionable, 85 for that they emit a disagreeable odor, which to a greater or less extent permeates the liquid of the bottle, and others are made of a material so loose that when the strain is brought to bear upon the stopper in screwing it in its 90 seat in the bottle the screw-threads will crumble or break off, and portions of it will drop into the liquid of the bottle when the stopper is removed, and I do not, therefore, broadly claim an elastic screw-stopper; but 95

What I do claim as new, and desire to secure by Letters Patent of the United States, is—

1. An elastic stopper for bottles and like vessels, consisting of leather rolled together 100 and secured by adhesive substance, and having a screw-thread formed on its periphery

adapted to fit a screw-thread in the neck of the bottle, as set forth.

2. The combination, with a stopper for bottles, consisting of leather rolled together and secured by adhesive substance, having a screw-thread on its periphery, of a bottle recessed on the inner side of its neck, with projections in the recess to receive and hold a leather socket, screw-threaded on its inner side,

adapted to receive the stopper, as and for the purpose set forth.

In testimony whereof I affix my signature in presence of two witnesses.

NATHAN SCHWAB.
